[57] CLAIM

The ornamental design for a video terminal or similar
article, substantially as shown and described.

DESCRIPTION

FIG. 1 is a front elevational view of a video terminal or
similar article showing my new design;

FIG. 2 is a right side elevational view thereof;

FIG. 3 is a top plan view thereof;

FIG. 4 is a bottom plan view thereof;

FIG. 5 is a left side elevational view thereof, the screen
being tilted forwardly relative to the base;

FIG. 6 is a right side elevational view thereof, the
screen being tilted rearwardly relative to the base;

FIG. 7 is a front perspective view thereof on a reduced
scale, the screen being turned to one side;

FIG. 8 is a rear perspective view thereof on a reduced
scale, a power switch, fuse and power cable being shown
in broken lines for illustrative purposes only.

FIG. 2

FIG. 1

FIG. 4

FIG. 3

FIG. 6

FIG. 5

FIG. 7
